UNITED STATES PATENT OFFICE.

JOSEPH F. JAMROWICZ, OF DETROIT, MICHIGAN.

DESIGN FOR A TIRE-TREAD.

59,008.

Specification for Design. Patented Sept. 13, 1921.

Application filed March 17, 1921. Serial No. 453,151. Term of patent 7 years.

To all whom it may concern:

Be it known that I, JOSEPH F. JAMROWICZ, a citizen of the United States, residing at Detroit, in the county of Wayne and State of Michigan, have invented a new, original, and ornamental Design for a Tire-Tread, of which the following is a specification, reference being had to the accompanying drawing, forming part thereof.

Figure 1 is an elevation of a tire tread showing my new design, and

Fig. 1 is a transverse section of the same.

I claim:—

The ornamental design for a tire tread, as shown.

JOSEPH F. JAMROWICZ.
